RADIO AERIAL ATTACHMENT

Application filed August 10, 1932. Serial No. 628,142.

This invention relates to radio aerial attachments, and more particularly to a device for connecting a shielded downlead to an antenna or other aerial and comprising a 5 matching impedance transformer.

In the use of radio broadcast receiving sets much annoyance is caused by noise due to interference by local electrical equipment, such as electrical refrigerators, door bells, 10 elevator motors, etc. Mostly such interference from such "man made static" is due to electrical disturbances induced in the downlead from the aerial to the receiving set. Disturbances induced in the aerial can 15 be prevented only by changing the construction or location of the aerial, but the downlead conductors may be and are commonly protected against picking up such electrostatic interference by providing the conductor with a metallic shield insulated from it and grounded, the shield usually being a metallic woven or other flexible tubing covering the insulated conductor.

Such shielded downlead conductors, while 20 they serve well to eliminate electrostatic interference from local sources, have the disadvantage that they cause a large loss in the signal energy reaching the receiving set, this being due to the large capacity between 25 the conductor and the shield as compared to the capacity of the aerial. The effective capacity of a shielded conductor 75 feet long is from 10 to 30 times as great as that of the average receiving aerial or antenna. The 30 capacitive reactance of a shielded downlead conductor is therefore small in comparison to that of the antenna, and, consequently, a considerable amount of energy is wasted and the power delivered through the downlead from the aerial is far from the maximum possible. In many cases, because of the desirability of having the antenna set so as to avoid inductive disturbance from local sources, and because of other conditions, 35 the receiving set is positioned at a considerable distance from the aerial; and because of the necessarily long shielded downlead the signal strength is greatly diminished. Even with a comparatively short shielded 40 downlead there is a very considerable loss.

This loss, resulting from the use of a shielded downlead, has been overcome by connecting an impedance matching transformer between the shielded downlead and the aerial, and this makes it possible to have 55 the aerial positioned so as in most cases to avoid disturbances induced in the aerial from local sources, with the result that full strength operation of the set may be secured without interference from "man made 60 static" even under severe conditions of proximate electrostatic disturbance. It has been demonstrated that when so connected to the 65 aerial, a receiving set will operate with very nearly the same signal strength when positioned as much as 300 feet from the antenna as when substantially directly connected therewith and free of metallic shielding.

The present invention aims to provide a 70 device for connecting a shielded downlead to an aerial with an impedance matching transformer between the downlead and the aerial which may be quickly and conveniently attached directly to the aerial or to a 75 lead therefrom at any desired point therealong. A further object of the invention is to provide such a device which is adapted to add to the electrical pick-up character- 80

istic of the aerial. 85 To these ends, the invention in the preferred embodiment comprises an impedance matching transformer mounted within a housing formed by a metal shell open at the bottom and a bottom closure of insulating material, and having a connecting member extending from the top of the casing formed for attachment to and for making electrical connection with the aerial, and provided with means for connecting the transformer to the downlead conductor and to ground. Such an embodiment of the invention is illustrated in the accompanying drawing, in 90 which:—

Fig. 1 is a view in elevation showing an 95 installation including the downlead connecting device of the invention;

Fig. 2 is a sectional view on a larger scale 100 of the connecting device;

Fig. 3 is a detail sectional view taken on line 3-3 of Fig. 2;

Fig. 4 is a circuit diagram showing the electric circuits of the device as shown in Fig. 2; and

Figs. 5 and 6 are circuit diagrams illustrating alternative arrangements.

Referring to the drawing, Fig. 1 shows a typical installation in which the downlead connecting device T, which provides an impedance matching transformer connected between the aerial and the receiving set, is shown as suspended from an antenna aerial A and having connected to it a shielded downlead conductor S leading to a radio-receiving set indicated at R. The shielded conductor comprises an insulated conducting wire or cable s which as shown is covered by a shield s' of woven wire or other flexible tubing. Both the conductor s and the shield s' are connected to the transformer of the device T, and at the set end the conductor s is connected to the antenna terminal a of the receiving set, and from the shield s' and the ground terminal g of the set a suitable ground connection is made as by a conductor g' connected to a water pipe w.

The downlead connecting device T as shown in Fig. 2 comprises an impedance matching transformer 10 within a casing formed by a metal shell 11 which is most desirably bell-shaped open at the bottom, and a bottom closing disc 12 of hard fiber sheet, the edge of the shell being shouldered and crimped over the edge of the disc. The transformer should, of course, be one suitable to serve the intended purpose of at least substantially reducing the difference between the impedance of the shielded downlead and that of the aerial. It should, therefore, be a step-down transformer in the direction from the aerial to the downlead, and for best results the impedance of its primary should substantially match the impedance of the aerial, and the impedance of its secondary should match substantially the impedance of the downlead conductor, and it should give maximum coupling. Because of its simple construction and the close coupling which it affords, we have found a suitable auto-transformer with multi-layer winding most desirable. Transformers of other forms might, however, be used.

Fig. 2 shows a simple form of a multi-layer auto-transformer consisting of a coil 15 wound on a bobbin formed by two dished fiber discs 16 and a spacing ring 17, the discs being held together by a centrally set eyelet 18. This transformer is mounted on the disc 12 and is held in place by a screw bolt 20 which extends through a central opening in the disc 12 and through a bushing 21 and the eyelet 18 to receive a nut 22 which when tightened on the bolt draws a flange 23 on the bolt against the outside of the disc 12.

The bolt 20 is connected by a terminal 24 and a lead 25 to an intermediate point of the coil 15, and the head 26 of the bolt extending from the outer side of the disc 12 is formed to serve as a connecting member for securing the end of the downlead conductor. The downlead conductor is thus connected through disc 12 to the secondary tap of the transformer coil.

The lead 30 from one end of the coil 15 is connected to a terminal 31 held by a nut 32 on a screw 33 which extends through an opening in the top of the shell 11 and the head of which is formed to provide a connecting member for attaching the device T to the aerial. The lead 40 from the other end of the coil 15 has connected thereto and extending out through an eyelet in the disc 12 a conductor 41 which serves as a connecting member for making a ground connection, usually by connection with the downlead shield as shown in Fig. 1. The portion of the coil between the secondary tap and the lead 40 serves as, and may be referred to as, the secondary of the transformer in addition to being part of the primary.

The construction of the connecting member by which the downlead connecting device is attached to the aerial will depend on the form of the aerial. This connecting member of the device shown by Figs. 1 to 3 is intended for attaching the device to an antenna wire, or to a wire leading from the antenna or other aerial. In the construction shown, the head 34 of the terminal screw 33 is made with a flat face and has a tapped hole to receive a clamping screw 35 and has a transverse slot 36. A washer 37 serves to clamp the antenna wire against the flat side of the head when the screw is tightened with the device positioned so that the antenna wire lies along the slot. The connecting device may thus conveniently be attached directly to the antenna or other wire so that the device will be suspended therefrom and electrically connected thereto. Connecting members of other construction will be provided for devices which are to be attached to other forms of aerials.

The device desirably has within the casing means providing a safety gap, or lightning arrester, connected across the transformer and the connection to the downlead conductor. For this purpose, a short fiber tube 50 is screwed on to the end of the terminal screw 33 and has in its other end a screw 51. The ends of the screws 33 and 51 are suitably pointed and spaced to provide a gap of the desired length, and connection is made from a terminal held by the screw 51 through an extension of the lead 40 to the ground connecting conductor 41, thus providing a normally open short-circuiting safety-gap connection from the antenna to

the ground shunting the transformer and the connection to the downlead conductor.

The space within the casing is desirably filled with wax or other suitable insulating

5 filling material. This serves the usual purpose of protecting the transformer coil against the condensation of moisture and gives added assurance against short circuiting.

10 Fig. 4 shows conventionally the electrical wiring of the device shown in Figs. 1 and 2. The ground connection G will usually be made through the shield of the downlead conductor as shown in Fig. 1 when the downlead cable has a shield which is a good conductor. Otherwise, as when using a lead-shielded cable, a separate grounding cable should be used, and this may be the second conductor which is commonly provided in 15 the lead-sheathed cables used as shielded downleads. If, instead of an auto-transformer, the device is provided with a two-coil transformer, the wiring connections may be as represented by Fig. 5. Fig. 6 shows 20 an arrangement in which the antenna is connected through the transformer coil to a counterpoise. In this case a second ground connection will be required from the secondary coil or secondary portion of the coil of 25 the transformer, and this will necessitate, as indicated by the diagram, a third connection from the transformer through the bottom disc of the connecting device casing.

30 The device of the invention whereby an impedance matching transformer and a shielded downlead may be attached directly to an antenna or other aerial or connecting wire leading therefrom has, as will be seen, important advantages. The installation of 35 the device is extremely simple, economical and practical. It is self-supporting and avoids the necessity of using any brackets or supporting structures for mounting the transformer to any wall, pipe or other such 40 support, and electrical losses due to faulty insulation under adverse weather conditions or otherwise are greatly reduced. The device may be connected at any point along 45 the length of an antenna. For certain types 50 of long aerials this is a distinct advantage for obtaining the best pick-up of a particular desired wave length. A further advantage of this downlead connecting device is that the metal shell of the casing adds sub- 55 stantially in some cases to the electrical pick-up obtained from the aerial. For a short antenna of say 20 to 25 feet in length the added electrical pick-up by the metal shell of this device will usually give a noticeable 60 improvement in the signal strength obtained, the improvement depending on the surface area of the shell, which may vary from a few inches to a square foot or more.

65 The terms "aerial" and "antenna" as used in the claims are to be construed as

including a wire or other conductor leading from the aerial or antenna proper to which the downlead connecting device may be attached.

What is claimed is:

1. The combination with a radio receiving aerial and a shielded downlead, of a device for connecting the downlead to the aerial comprising connecting means suspending the device from and making electrical connection to the aerial, an impedance matching transformer connected with said connecting means, and means connecting the transformer with the shielded downlead conductor and with ground. 70 75 80

2. The combination with a radio receiving aerial and a shielded downlead, of a device for connecting the downlead to the aerial comprising connecting means suspending the device from and making electrical connection to the aerial, and impedance matching transformer connected with said connecting means, and means connecting the transformer with the downlead conductor and the downlead shield. 85 90

3. A device for connecting a shielded downlead to a radio receiving aerial, comprising an impedance matching transformer, means for connecting the transformer with the downlead conductor and with ground, and a connecting member whereby the device may be suspended from the aerial and the transformer electrically connected thereto. 95

4. A device for connecting a shielded downlead to a radio receiving aerial, comprising a casing formed by a metal shell open at the bottom and a bottom closure of insulating material, a connecting member extending from the top of the casing and formed for attachment to and for making electrical connection with the aerial, connecting members extending from the bottom closure for connection to the downlead conductor and the downlead shield respectively, and an impedance matching transformer within the casing connected between the aerial connecting member and the downlead connecting members. 100 105 110

5. A device for connecting a shielded downlead to a radio receiving antenna, comprising a casing having a bell-shaped metal part and a bottom closing disk of insulating material, a connecting member extending from the top of the casing for attachment to and for making electrical connection with the antenna, an impedance matching transformer within the casing mounted on said bottom disk, a lightning arrester unit within the casing connected across the transformer, and means extending through the bottom disk for electrically connecting the shielded downlead conductor to the transformer. 115 120 125

6. A device for connecting a shielded

- downlead to a radio receiving aerial, comprising a casing having a bottom closing disk of insulating material, a connecting member extending from the top of the casing formed for attachment to and for making electrical connection with the aerial, an impedance matching transformer formed by a coil wound on a flat bobbin mounted flatwise on said bottom disk and secured by a bolt passing through the bottom disk and centrally through the bobbin and having an outside head formed to serve as a connecting member for the shielded downlead conductor, and a connection from said bolt 10 to an intermediate point of the coil, one end of the transformer coil being electrically connected with the top connecting member and the other end of the coil having a ground connection extending through said disk.
- 15 7. A device for connecting a shielded downlead to a radio receiving aerial, comprising a casing having a bottom closing disk of insulating material, a connecting member formed for attachment to and for making electrical connection with the aerial and having a screw stud which extends through the top of the casing and is held by an inside nut, an impedance matching transformer mounted on said disk and secured by 20 a bolt passing through the bottom disk and electrically connected to a secondary lead of the transformer and having an outside head formed to serve as a connecting member for the shielded downlead conductor, a short 25 tube of insulating material one end of which is screwed on to said screw stud, a gap terminal in the other end of said tube, the ends of said terminal and said screw stud being shaped and spaced to form a safety gap, one 30 primary lead of the transformer being electrically connected with said top connecting member, and a ground connection extending through said disk and connected to the other primary lead and to said gap terminal.
- 35 8. A device for connecting a shielded downlead to a radio receiving aerial, comprising an encased impedance matching transformer, means for connecting the transformer at different points to the downlead 40 conductor and downlead shield respectively of a shielded downlead, and means for suspending the unit from the aerial and for making electrical connection between the aerial and the transformer.
- 45 9. A device for connecting a shielded downlead to a radio receiving aerial, comprising an encased impedance matching transformer, means for connecting the transformer at different points to the downlead 50 conductor and downlead shield respectively of a shielded downlead, and means, comprising a post rigid with said casing and having a clamp, for suspending the unit from the aerial and for making electrical connection 55 between the aerial and the transformer.
10. A device for connecting a shielded downlead to a radio receiving aerial, comprising an impedance matching transformer, a casing within which the transformer is mounted, means including a post 70 projecting from the lower part of the casing and a wire lead for connecting the transformer at different points to the downlead conductor and downlead shield respectively of a shielded downlead, and means, comprising a post rigid with and electrically connected to said casing, for suspending the unit from the aerial and for making electrical connection between the aerial and the 75 transformer.
11. In a device of the character described, a housing comprising a metal shell and a bottom of insulating material, an impedance matching transformer fixed within said housing and electrically connected to said metal shell, a binding post projecting from the top of said metal shell in electrical connection therewith, a binding post depending from said bottom in electrical connection with said transformer and having a shank 80 and locking means for securing the transformer to said bottom, and a lead from said transformer extending through said bottom to make electrical connection with the shield of a shielded downlead when the downlead conductor is attached to the bottom binding post.
12. In a device of the character described, a housing comprising a metal shell and a bottom of insulating material, an impedance matching transformer fixed within said housing and electrically connected to said metal shell, a binding post projecting from the top of said metal shell in electrical connection therewith, a binding post depending from said bottom in electrical connection with said transformer and having a shank 85 and locking means for securing the transformer to the bottom, and a lead from said transformer extending through said bottom to make electrical connection with the shield of a shielded downlead when the downlead conductor is attached to the bottom binding post.
13. In a device of the character described, a housing comprising a metal shell and a bottom of insulating material, a substantially flat impedance matching transformer on said bottom within the housing, a post extending centrally through and fixed to said bottom having locking means for securing the transformer on the bottom and a 90 projection with terminal clamp outside the housing, a post extending centrally through and fixed to and in electrical connection with said shell and having a clamp outside the housing and spaced conductors inside pro- 95
14. In a device of the character described, a housing comprising a metal shell and a bottom of insulating material, a substantially flat impedance matching transformer on said bottom within the housing, a post extending centrally through and fixed to said bottom having locking means for securing the transformer on the bottom and a 100 projection with terminal clamp outside the housing, a post extending centrally through and fixed to and in electrical connection with said shell and having a clamp outside the housing and spaced conductors inside pro- 105
15. In a device of the character described, a housing comprising a metal shell and a bottom of insulating material, a substantially flat impedance matching transformer on said bottom within the housing, a post extending centrally through and fixed to said bottom having locking means for securing the transformer on the bottom and a 110 projection with terminal clamp outside the housing, a post extending centrally through and fixed to and in electrical connection with said shell and having a clamp outside the housing and spaced conductors inside pro- 115
16. In a device of the character described, a housing comprising a metal shell and a bottom of insulating material, a substantially flat impedance matching transformer on said bottom within the housing, a post extending centrally through and fixed to said bottom having locking means for securing the transformer on the bottom and a 120 projection with terminal clamp outside the housing, a post extending centrally through and fixed to and in electrical connection with said shell and having a clamp outside the housing and spaced conductors inside pro- 125
17. In a device of the character described, a housing comprising a metal shell and a bottom of insulating material, a substantially flat impedance matching transformer on said bottom within the housing, a post extending centrally through and fixed to said bottom having locking means for securing the transformer on the bottom and a 130 projection with terminal clamp outside the housing, a post extending centrally through and fixed to and in electrical connection with said shell and having a clamp outside the housing and spaced conductors inside pro-

viding a safety gap, connections from said transformer to the bottom post and to the shell post, and a lead from said transformer through said bottom for connection to the shield of a shielded downlead connected to the bottom post, said lead having a connection with one of said spaced conductors.

14. The combination with a radio receiving aerial and a shielded downlead, of a device for connecting the downlead to the aerial comprising a casing, means for suspending the casing from the aerial, an impedance matching transformer within the casing, connecting means for connecting the primary of the transformer to the aerial and the primary and secondary of the transformer to ground, and means for connecting

the secondary of the transformer to the downlead conductor.

15. The combination with a radio receiving aerial and a shielded downlead, of a device for connecting the downlead to the aerial comprising a casing, means for suspending the casing from the aerial, an impedance matching transformer within the casing, connecting means for connecting the primary of the transformer to the aerial and the primary and secondary of the transformer to the downlead shield, and means for connecting the secondary of the transformer to the downlead conductor.
